UNITED STATES PATENT OFFICE.

JOHN BRETZ, JR., OF DETROIT, MICHIGAN.

FUEL-HEATER.

1,296,043.

Application of Letters Patent. Patented Mar. 4, 1919.

Application filed November 20, 1917. Serial No. 202,923.

To all whom it may concern:

Be it known that I, JOHN BRETZ, Jr., a citizen of the United States of America, residing at Detroit, in the county of Wayne and State of Michigan, have invented certain new and useful Improvements in Fuel-Heaters, of which the following is a specification, reference being had therein to the accompanying drawings.

10 This invention relates to an automatically controlled fuel heater, and more particularly to a heating unit particularly adaptable for use in connection with carburetors or other fuel supplying means for internal combustion engines.

The primary object of my invention is to provide means for quickly raising the temperature of fuel passing through a carburetor or other fuel supplying device to make 20 the fuel more volatile and thus aid in starting the engine, and further, to automatically control the operation of such means to maintain the temperature of the fuel above a predetermined point to give greater efficiency 25 and economy in running the engine. It is also an object of the invention to so construct an electrical heating device and embody therein a thermostatic control, that the same, as a unit, may be readily connected to 30 a carburetor as ordinarily constructed and will form a supplemental fuel chamber therefor within which the heating element is inclosed and immersed in the fuel, whereby a small quantity of fuel is quickly heated for 35 starting the engine and the temperature of the fuel passing through this chamber to the engine, automatically controlled during the running of the engine.

A further object of my invention is to 40 attain the above and other objects by a simple, durable and inexpensive mechanical construction which is hereinafter specifically described and then claimed.

Reference will now be had to the drawing, 45 wherein—

Figure 1 is a side elevation of a conventional form of carburetor, partly broken away and partly in section, showing the electrical heating device attached thereto and in 50 section; and

Fig. 2 is an enlarged vertical sectional view of the electrical heating device as applied to a carburetor bowl or outer fuel receptacle.

As illustrating an embodiment of the invention, there is shown a conventional form

of carburetor comprising a body 1 provided with a float chamber 2 adapted to supply a fuel, as gasoline or kerosene to a nozzle 3 in a Venturi tube extending into an engine 60 manifold connection 5. This type of carburetor ordinarily has a detachable bottom plug which permits of the carburetor being drained, and to install my electrical heating device, it is only necessary to remove the bottom plug and substitute my device therefor.

The electrical heating device comprises a tubular member 6 having the lower end thereof closed and the upper end exteriorly screwthreaded, as at 7, in order that it may 70 be mounted in the lower end of the carburetor body 1 and held snugly in engagement therewith by a washer 8, a nut 9 or other fastening means.

At one side of the tubular member 6 is a 75 casing 10 having a detachable cover 11. Connected to the inner side of the cover 11 by a set screw 12 or other fastening means is a bracket 13 which is insulated from the cover 11.

Supported by the upper end of the bracket 13 and insulated therefrom is a contact arm 14 having the properties of a thermostat, that is, said contact arm is made of two strips of different kinds of metal having different 85 properties of expansion and contraction, so that upon being heated the lower end of the contact arm will move to and from an adjustable binding post 15 carried by the casing cover 11 and suitably insulated therefrom. The adjustable binding post 15 has a lead-in wire 16 connected thereto and by adjusting said binding post the making and breaking of an electrical circuit can be regulated to operate at desired degree of heat. 95

The upper end of the contact arm 14 is adapted to engage a resilient member 17 carried by a wall of the tubular member 6 and insulated therefrom, said resilient member being held by a binding post 18.

Mounted in the lower end of the tubular member 6 and insulated therefrom is a binding post 19 to which is connected another lead in wire 20, this wire as well as the wire 16, being adapted for connection with a suitable source of electrical energy as a generator or battery.

The binding posts 18 and 19 are connected by a resistance coil 21 adapted to be heated by an electrical current passing therethrough. The resistance coil 21 may be insulated from the casing walls in any suitable

manner as by providing suitable insulation material thereon, or as shown by a jacket of insulation material 22 mounted in the lower end of the tubular member 6 and held by 5 the binding post 19. Then again it is possible to line the walls of the tubular member 6 with porcelain or other insulating material so as to prevent a short circuit and maintain the resistance coil 21 in operative 10 condition when a current of electricity is passed therethrough.

By reference to Fig. 1, it will be observed, that the tubular member 6 is in communication with the float chamber 2, so that before 15 fuel may enter the nozzle 3, the fuel will flow into the auxiliary chamber in the member 6 and submerge the resistance coil 21 to be heated thereby. By adjusting the binding post 15, which serves as a contact 20 member, it may be set so that a very low temperature will affect the thermostatic arm 14 sufficiently to cause it to spring out of contact with the binding post 15 to open the electrical circuit and stop the passage of 25 current therethrough, the resistance coil 21 stopping the further heating of fuel as soon as it has been raised to the desired and predetermined temperature. As soon as the 30 temperature falls below this predetermined point the thermostatic arm 14 will again straighten out and close the electric circuit until such time as the temperature of the fuel is again raised above the point determined by the adjustment of the terminal 35 screw 15. It is therefore apparent that the electrical device is automatic in its operation and that such operation may continue as long as an engine is in operation or the 40 current is turned on to the circuit of the resistance coil.

I attach considerable importance to the fact that the electrical device is in the form of an attachment applicable to the several well known types of carburetors, and that 45 with the casing 10 for the thermostat placed at one side of the tubular member and made a part of the structure, the device may be applied to a carburetor as a unit without altering the carburetor or other engine appurtenances in proximity thereto. Obviously 50 the connection 7 may be formed in any desired position upon the member 6 to facilitate the connecting of the device to the particular carburetor to which it is to be applied, the heating coil being operable in any 55 position, it only being necessary to so connect the members 6 with the fuel supply, that the fuel will flow into the heating chamber.

60 From the foregoing it will be noted that my invention involves a fuel chamber to receive fuel, a heating element in the chamber, and a thermostatic control element adjacent

to the chamber to be affected by the temperature of fuel in said member and automatically control the operation of the electrical heating element, the making of the device perfectly automatic at all times, and further that the thermostat may be adjusted to operate when the desired degree of heat 70 has been attained.

One embodiment of my invention has been illustrated, but it is to be understood that the structural elements are susceptible to such variations and modifications as fall 75 within the scope of the appended claims.

What I claim is:—

1. The combination with a carburetor, of a member connected thereto and adapted to receive fuel therefrom, a casing carried by 80 one side of said member, an electric heating device in said member adapted to be connected to a source of electrical energy, and a thermostatic control element within said casing in circuit with said heating device 85 and the source of electrical energy and adapted to automatically control the operation of said heating device.

2. A heater unit comprising a body formed with a fuel chamber and a thermostat chamber, means for connecting the body to a carburetor affording communication between the carburetor and fuel chamber, a heating coil in the fuel chamber and a thermostat in the thermostat chamber 95 within the circuit of the heating coil.

3. An electrical heater for carburetors comprising a body formed with a fuel chamber and a thermostat chamber, means forming an open connection between the interior of a carburetor and the fuel chamber, a heating coil in the fuel chamber, an electrical circuit for the coil, a detachable cover for the thermostat chamber, and a thermostat on said cover within the electrical circuit. 100

4. An electrical heater for carburetors comprising a body formed with a fuel chamber and a thermostat chamber, means for forming an open connection between the 110 interior of a carburetor and the fuel chamber, a heating coil in the fuel chamber, a terminal member connected with the coil and extending into the thermostat chamber, a detachable cover for the thermostat chamber, and a thermostat device carried by the 115 cover and adapted to be held in electrical connection with the coil terminal member when the cover is secured in place.

In testimony whereof I affix my signature 120 in the presence of two witnesses.

JOHN BRETZ, JR.
